UNITED STATES PATENT OFFICE.

ROBERT ARTUS, OF GERA, GERMANY.

ICE MACHINE.

Application filed September 9, 1925, Serial No. 55,401, and in Austria June 2, 1925.

This invention relates to improvements in ice-machines particularly machines for manufacturing limited quantities, and it is the principal object of the invention to provide an ice-machine mounted in an oscillating frame suspended by means of pendulum arms.

Another object of the invention is the provision of an ice-machine, the water bottle and acid container of which are removably arranged within the frame and which are connected by means of a special connection ending within the acid container in a glass tube having a flange so that the air removed from the water container is discharged through the acid being in a state of agitation.

A further object of the invention is the provision of an ice-machine embodying a vacuum-pump the piston rod of which operates in a stuffing box which is provided with an oil seal.

A still further object of the invention is the provision of an ice-machine equipped with a pump connected with an oil-catcher embodying a plurality of oil deflecting plates.

The invention furthermore includes a means for operating the ice-machine by means of a motor, the shaft of which is coupled in a peculiar manner with the shaft of a worm gear and crank producing the oscillation of the frame and also a transmission coupling coupling the pendulum arms by means of a slide-coupling to the operating mechanism while said arms are rotatably attached to the frame standard.

These and other objects and advantages of my invention will become more fully known as the description thereof proceeds and will then be more specifically defined in the appended claim.

In the accompanying drawing forming a material part of this disclosure:

Fig. 1 is a front elevation of the ice-machine constructed according to my invention.

Fig. 2 is a top plan view thereof.

Fig. 3 is a detail view of the transmission device.

Fig. 4 is a vertical section through the air pump and oil box.

Fig. 5 is a section through the upper part of the acid bottle.

A base frame *a*, carries removably the two containers *b* and *c* for the reception of acid and water respectively. The frame *a* is

mounted to oscillate between standards *d* by means of the rotatably suspended pendulum arms *e*.

The acid container *b* is oscillated by arm *f* fulcrumed at *g* and connected at one of its outer ends to one of the arms *e*.

The water bottle *c* is preferably made in parts in order to facilitate the removal of the ice to be made therein, and is connected to the acid container *b* by means of a pipe connection *h*. A valve *h*¹ is provided in the connection at the knee thereof leading to the water container, adapted to allow the admission of air after the termination of the refrigeration or ice-making process.

The pipe *h* is attached at its opposite end to the knee-piece *h*² of the acid container *b* and the other end of the knee-piece *h*² is connected to a glass tube *j* within the upper part of the acid container.

The glass tube enters the acid container *b* and extends therein to the level of the acid. Within the neck part of the acid container the tube *j* has a flange *j*¹ (Fig. 5) preventing a scattering of the acid and entering of the same into the upper part of acid container *b*.

The flanged cover *b*¹ of the acid container is provided with a bore in communication with a hollow stem *b*² of pipe *l* leading to the pump *k*, and a valve near the stem *b*² is intended for preventing the oil collecting eventually within the lower part to come in contact with the acid.

The air pumped out of the water bottle in the ordinary well known manner in order to create a vacuum in said bottle, is led through the pipe *h*, the knee-part *h*² and the glass-tube *j* into the acid container, and from the latter is guided around the glass tube in the direction of the arrows into the upper part of the acid container and from there through stem *b*² into the air pipe *l* and through the same to the pump *k* or its cylinder. The piston of the pump has an oil seal towards the outside and the oil is contained within the upper part of the pump cylinder.

In order to prevent the oil from leaking into the lower part of the cylinder, and to effect simultaneously a tight closure to preserve the vacuum, the piston rod *k*¹ is passing through a stuffing box *k*² which is held under tension by means of a spring *k*³ and an air tight closure is provided by means of *k*⁴ the leather washers *k*⁴. A piston valve *k*⁵ effects the regulation of the air suction.

The sucked-on air passes under considerable pressure into the oil chamber of the pump, and it will be clear that during the discharge of the air, a scattering of the oil 5 would be unavoidable. In order to prevent this an oil catcher is provided at the air discharge of the pump. This oil catcher comprises a metal box m having a removable cover n and a plurality of inclined oil catching plates m^1 having their ends spaced from the inner wall of the box. It will be clear 10 that the oil carried along with the pumped out air will be arrested at the plates under the action of the centrifugal force and will 15 flow back into the oil chamber when the pump is not working.

If an operation of the ice-machine by motor o is desired, the shaft p of which engages the shaft q of a worm gear, and both shafts 20 are coupled elastically by means of a spring s held in position on both shafts by means of tension pins or screws, or the like.

The motion of shaft q is transmitted by 25 means of a worm r arranged within a suitable housing engaging a worm wheel t to the same by suitable means of translation to lower the high number of revolutions developed by the motor shaft.

The oscillation of the frame is produced 30 by means of a crank u on the shaft of the worm wheel t to which a rod v is attached which engages the rod f fulcrumed at g and transferring the motion to the pendulum arm c .

35 The opposite end of rod f is guided within a slide w so that the pendulum rod e re-

ceives an up and down motion as it is rotatably secured to the frame.

In this manner a uniform oscillation of the frame, favoring a quick formation of the 40 ice, is effected.

It will be understood that while I have shown and described as an example the preferred embodiment of my invention, the same can be subjected to many changes in 45 its general arrangement and in the construction of the minor details thereof, without departure from the spirit of the invention.

Having thus described my invention what I claim as new and desire to secure by Letters Patent, is:

In an ice-machine of the class described comprising a plurality of standards, an oscillating frame suspended between said standards, a motor on said standards having a shaft, a worm, a shaft for said worm, and a spring coupling motor shaft and worm shaft, a worm wheel in mesh with said worm, a crank arm on the shaft for said worm wheel, a rod attached to said crank arm and to the frame for oscillating the same, a water bottle and an acid container removably suspended from said frame, a vacuum pump, a connection between said acid container and said vacuum pump, a connection between 60 said container and said bottle, and a compensating valve for compensating the vacuum in said bottle.

Signed at Gera, in the county of Reuss, and State of Germany, this 24th day of July, 70 A. D. 1925.

ROBERT ARTUS.
